UNITED STATES PATENT OFFICE.

ERIC A. NASLUND, OF DUNKIRK, NEW YORK.

APPARATUS FOR CATCHING AND DELIVERING MAIL-BAGS.

No. 847,682.

Specification of Letters Patent.

Patented March 19, 1907.

Application filed April 10, 1905. Serial No. 254,807.

To all whom it may concern:

Be it known that I, ERIC A. NASLUND, a citizen of the United States, residing at Dunkirk, in the county of Chautauqua and State 5 of New York, have invented certain new and useful Improvements in an Apparatus for Catching and Delivering Mail-Bags, of which the following is a specification.

This invention relates to an improved 10 apparatus for catching and delivering mail-bags.

The invention has for its object to provide an apparatus which will deliver and take up mail-bags at a point below the level of the 15 car-floor, inclose within a receiving-chamber the bag delivered, and lock the latter within said chamber automatically, to provide an apparatus which is simple and durable in construction, reliable in action, and in which 20 the number of parts employed is reduced to a minimum, and to provide a crane in which the catching and delivering arm is counterbalanced to render the same easy to operate.

Further objects are to provide a combined 25 bag catching and delivering arm, to provide a removable crane which can be used at either side of the car, to provide for automatically diminishing the extent of projection of said arm, so that it may easily be 30 swung through the car-door, and to otherwise improve on mail catchers and deliverers now in use.

To these ends the invention consists in the 35 construction, arrangement, and combination of parts and devices to be hereinafter described, and particularly pointed out in the appended claims.

In the accompanying drawings, Figure 1 is a side elevation of a portion of a car provided with my improved bag catcher and deliverer and a longitudinal section of the bag-receiver, the latter being open to receive the mail-bag carried on the crane and support a bag to be taken up by said crane. 40 Fig. 2 is a similar view showing the crane after having deposited a bag in the receiver and taken up the bag supported on said receiver. Fig. 3 is a side elevation of a portion of a car, showing the arm of the crane elevated and swung into the car. Fig. 4 is a vertical section taken on the planes indicated by line yy , Fig. 1. Fig. 5 is a top plan view of the receiver with the cover open. Fig. 6 is an enlarged central vertical section 45 taken on line zz , Fig. 2, the inner end portion of the arm only being shown. Fig. 7 is an

enlarged detached perspective view of the upper bearing or support for the upright of the mail-crane. Fig. 8 is an enlarged perspective view of the lower bearing or support for the crane having combined therewith a buffer to take up the jar of the arm when lowered and when taking up and delivering a mail-bag. Fig. 9 is a detached perspective view of the bag-support which 60 serves to control the opening and closing of the receiver.

Referring now to the drawings in detail, like numerals of reference refer to like parts in the several figures.

The numeral 1 designates a car to which the catching and delivering crane 2 of my improved apparatus is applied, and 3 designates the bag-receiver supported on the ground to one side of a track or between tracks. In 70 the latter case the receiver may be lengthened and the operating parts duplicated and reversed to form a double-ended receiver.

The catching and delivering crane comprises an upright or post 4, located adjacent 80 the car-door jamb and a short distance from the outer edge of the floor to permit of opening and closing the car-door. Said upright is hollow and supported on a casting 5, having a gudgeon 6 entering the lower end of the upright. At the upper end of the car-door opening a socket 7 is secured, which is open at one side, as at 8, and in the parallel walls 9 of said socket are aligned openings, into which a pin 10 is placed whose function is to retain 85 the upper end of the upright in said socket. By fastening the upright in this manner it can be quickly detached and placed on the other side of the car, there being similar castings or fittings 5 and 7 respectively arranged 90 in corresponding relation to the opposite car-door opening, thereby providing for the use of the apparatus on the car irrespective of the direction of travel.

A mail-bag arm or, more specifically, a 100 combined delivering and catching arm 11 is slidably and rotatably held to the upright and comprises a sleeve portion 12, surrounding the upright and having a radial extension 13, hollowed out to form a pocket 14 and the 105 arm proper, 15, which has its inner end held within the said pocket and pivotally attached therein at the upper inner corner, so as to allow said arm a vertical swinging movement to a limited extent. The limit of 110 said movement is governed by the difference in the relative angles of the inner and upper

sides of the arm proper and the inner and upper walls of the pocket 14, a space being either between the inner side of the arm and the inner wall of the pocket or between the upper side of the arm and the upper wall of the pocket, depending as to whether the sleeve is elevated or lowered on the upright.

Within the upright is a counterbalance in the form of a cylindrical weight 16, which is movable in said upright and suspended from a cord 17, passing over a pulley 18, journaled on said upright and positioned within a slot in the latter, so as to extend partly within and partly without said upright. Said cord 15 has its opposite end attached to the bag catching and delivering arm, as at 19, and with said counterbalance renders said arm easy to raise and lower.

The bag catching and delivering arm is held in an inclined position at all times, and its outer end when lowered is below the level of the car-floor and extends to the center of the bag-receiver 3, which must be located a certain distance from the center of the track 25 over which the car passes in order to avoid all projecting parts of passing trains. The distance between the upright and the distant jamb of the door-opening is much smaller in some cars than the distance between said upright and the center of the bag-receiver when said upright is opposite the latter, and therefore when the catching and delivering arm is lowered on the upright it comes in contact with a rubber or other suitable cushioning-buffer 20, held within flanges on the casting 5, and is caused to swing upward on its pivotal point toward a line perpendicular to the upright until stopped by the upper face thereof striking the upper wall of the pocket 14. 30 Said buffer serves to take up the jar and renders the device substantially noiseless.

When it is desired to swing the catching and delivering arm into the car, it must be elevated to bring the outer end thereof above the car-floor, and in so doing the pivoted portion of the arm continues to bear against the buffer while the sleeve portion is passing through the initial portion of its upward movement, and during such action the pivoted portion swings downward and inward until the inner end of the same comes in contact with the inner wall of the pocket 14. During this movement the distance on a horizontal plane between the outer end of said arm and the axial line of the upright is considerably lessened, and the arm as soon as entirely elevated above the floor can be conveniently swung inward through the door. On many cars a perfectly-rigid arm can be used, as the door-openings are of sufficient width to permit of swinging the arm into the car without providing means to lessen the distance on a horizontal plane between the support and the outer end of the arm, while 60 in some cars I have found it necessary to pro-

vide for a greater compensation than could be given by a device constructed in the relative proportions and measurements shown. This, however, can be easily accomplished by changing the relative angles of the inner and upper walls of the pocket 14 and the inner and upper sides of the pivoted portion of the arm.

The construction herein shown is merely a representative one, and the purposes for which it is designed can be accomplished in various other ways without departing from the fundamental principles involved.

The outer end of the bag catching and delivering arm is provided with a catching device 21 and a delivering device 22, arranged forward of and in rear of said arm, respectively. The catching device comprises two parallel forwardly-extending arms 23, separated by an intervening bag-receiving space 24, the upper of said arms being bifurcated to receive an elbow lock-bar 25, pivotally attached to the outer end thereof and adapted for movement in a vertical plane. The normal position of the lock-bar is that shown in Fig. 1, in which it has one member extending horizontally from the end of the upper arm 23 and its other member extending vertically to the outer end of the lower arm, it being held in this position by a spring 26, secured to the upper arm and bearing with its end against the angular portion of said lock-arm directly above its pivotal point.

The delivering device 22 likewise comprises two parallel arms 27, which extend, however, in an opposite or rearward direction. The upper of these arms has pivotally attached thereto a retainer-loop 28, which is designed to engage the lower of said arms and retain a mail-bag 29 thereon. Said loop engages the lower arm 27 with sufficient frictional contact to prevent accidental disengagement of the mail-bag from said arm. In placing the mail-bag in the delivering device it is hung onto the lower arm with the ends suspended, as shown in Figs. 3 and 4. By preference the delivering device and the catching device are formed integrally with the pivot portion of the mail-bag arm.

It is to be noted that by reason of the pivoted portion of the bag catching and delivering arm being pivotally attached to the slideable sleeve portion near its upper end and having its inner end bearing against said sleeve portion throughout its length the tendency of the same is to pull on the upper end of said sleeve portion and exert pressure against the lower end thereof, which tends to cause binding of the sleeve portion on the upright and hold the arm in any position to which it may be elevated. By relieving the sleeve portion of this tendency the arm can be quickly and easily raised and lowered.

The receiver 3 is in the form of a shallow

box or receptacle, by preference of rectangular formation and closed on all sides with a gate or cover 30, having collapsible sides consisting of a rigid section 31 and a swinging section 32. The cover is fulcrumed between its ends, as at 33, and has one end weighted, as at 34, to check the closing of the longer portion lying on the opposite side of the fulcrum-point. A bag-support 35 is pivotally secured to the cover and comprises in representative form a yoke or U-shaped casting 36, having at the upper ends of its arms forwardly-extending bars 37, onto which the mail-bag 38 is laid, with the ends thereof hanging down on opposite sides, and a shank or lever portion pivotally affixed to the top of the cover, as at 39, with the end thereof extending into the receiver through a slot 40 in said cover. A cross-bar 41 connects the inner ends of the swinging section 32 and has secured thereto the inner end of the bag-support 35 or, more properly, the inner end of the lever portion of the bag-support. The outer ends of said swinging sections of the cover are connected to the rigid sections thereof by links 42. Secured to the top of the cover are bag-retainers in the form of upwardly-curved and forwardly-extending bars 43, onto which the end loops or straps 44 of the mail-bags are to be hooked, as clearly shown in Fig. 1, said bag serving as a connection between the bag-support and the cover to hold the latter open.

As shown in Fig. 1, the bag-receiver is open to receive the bag carried on the delivering device of the mail-crane, the free end of the catching and delivering arm being arranged to clear the cover. As the crane passes the receiver the mail-bag on the delivering device comes in contact with the elevated end edge of the cover and is held against further movement with the car. This action causes the lower arm of the delivering device to be withdrawn from beneath the bag and the retainer-loop 28 to be forced out of contact with the said arm. The forward movement of the car under speed causes the detached bag to be delivered through the open end 45 of the cover into the receiver.

The arm of the crane immediately after the bag is detached from the delivering device passes over and between the yoke portion of the bag-support 35, with the two arms of the catching device passing above and below the center portion of the bag-support thereon, so as to straddle the same. When the arm of the crane comes in contact with the bag to be taken up, the loops 44 on the latter are disengaged from the bag-retainers 43, and the lock-bar 25 is moved from its receiving or open position, (shown in Fig. 1,) to its locked position, (shown in Fig. 2,) the bag held on the catching device being thus locked onto the latter against accidental disconnection.

When the mail-bag is removed from the bag-support 35, the cover closes automatically, the swinging sections of the sides swinging with their outer ends through slots 46 in the cover and the bag-support swinging 70 against the cover, as shown in Fig. 2, provision being made to permit the forwardly-extending bars 37 of the support to enter the receiver by forming in said cover slots 47, through which said bars are passed. As the 75 cover closes a spring-lock 48 of any suitable form locks the receiver. This lock may have a spring-bolt 49, which is adapted to enter a notch 50 in one of the sides of the cover.

By providing collapsible sides for the 80 cover a shallow receiver can be used, thereby avoiding the necessity of embedding the receiver in the ground, which would be objectionable by reason of water oozing through the crevices and in cold weather freezing and 85 rendering the apparatus inoperative. With this construction the receiving-opening 45 in the cover can be made considerably larger than the height of the receiver.

As the catching and delivering arm comes 90 into action to deliver or take up a mail-bag a violent contact is made and the arm given a sudden jar. The cushioning-buffer 20 is therefore provided with a vertical extension 51, against which the side of the arm bears 95 and serves to take up the jar imparted thereto. In this manner the noise incident to delivering and taking up the mail-bags is reduced to a minimum, as is also the jar to which the crane is subjected.

Many alterations in construction, form, and arrangement of parts may be resorted to without departing from the scope of my invention, or substitute parts or devices may be employed by means of which similar functions or purposes may be carried out, and such substitution I do not consider as departures from my invention, but lay full claim to the same.

Having thus described my invention, what 110 I claim is—

1. The combination with the car, of an arm projecting therefrom and having at its outer end a pair of forwardly-projecting arms and a pair of rearwardly-projecting arms, 115 serving respectively as a catching device and a delivering device the arms of each pair being arranged one above the other and separated by an intervening space.

2. The combination with the car, of an arm projecting therefrom and having at its outer end a pair of forwardly-projecting arms and a pair of rearwardly-projecting arms, and retaining devices between the free ends of each pair of arms.

3. The combination with the car, of an arm projecting therefrom and having at its outer end two forwardly-projecting arms and two rearwardly-projecting arms, an elbow lock-bar for the forwardly-projecting arms, 125 130

and a retainer-loop for the rearwardly-projecting arms.

4. The combination with the car, of an arm projecting therefrom and having at its outer end two forwardly-projecting arms arranged one above the other and separated by an intervening space and two similarly-arranged rearwardly-projecting arms, an elbow lock-lever pivotally secured to the upper of the forwardly-projecting arms, and a loop pivotally secured to the upper of the rearwardly-projecting arms and adapted to engage the lower of said arms.

5. In a mail catching and delivering device, an arm having a pair of forwardly-projecting arms, an elbow lock-bar pivotally secured to one of the forwardly-projecting arms, a spring serving to hold said lock-bar against accidental movement, and a loop pivotally secured to one of the rearwardly-projecting arms and adapted to embrace the free end of the other of said arms.

6. The combination with the car, of a vertical support secured to the car, and a projecting arm slidable on said support and embodying means to deliver the mail while the car is in transit.

7. The combination with the car, of a vertical support secured to the car, and a projecting arm slidable on said support and embodying means to catch the mail while the car is in transit.

8. The combination with the car, of a vertical support secured to the car, an arm projecting from the car and being slidably and rotatably mounted on said support, and a mail-catching device at the outer end of said arm.

9. The combination with the car, of a support secured thereto, and a mail-bag arm secured to said support and comprising a sleeve slidable on said support and a pivoted arm portion.

10. The combination of a car, of a support secured thereto, and a mail-bag arm slidable and rotatable on said support and comprising a sleeve on said support and an arm portion pivotally secured to said sleeve.

11. The combination with the car having an opening, a support secured to the car, a mail-bag arm rotatable on said support, and means to lessen the distance in a horizontal plane between the support and the outer end of said arm to permit of conveniently swinging the latter through said opening.

12. The combination with the car having an opening, an upright secured to the car, a mail-bag arm rotatable on said upright and comprising a sleeve and an arm portion pivotally secured to said sleeve so as to swing in a vertical plane.

13. The combination with the car having an opening, of a cylindrical upright secured to the car and a mail-bag arm slidable and rotatable on said upright and comprising a

sleeve on the latter having an extension providing a downwardly and outwardly opening pocket and an arm portion pivotally secured in said pocket and having its inner and upper sides arranged at a more acute angle than the angle of the top and inner walls of said pocket.

14. The combination with the car having an opening, of an upright secured to the car, a mail-bag arm slidable on said upright, and means for swinging said arm toward a horizontal plane when lowered on said upright.

15. The combination with the car having an opening, of an upright secured to the car, an inclined mail-bag arm slidable on said upright, and means for causing said arm to swing toward a horizontal plane as it approaches its lowermost point on the upright.

16. The combination with the car having an opening, of an upright secured to the car, a mail-bag arm slidable and rotatable on said upright and having a pivoted inclined portion adapted to come in contact with the floor of the car before said arm reaches its lowermost point, thereby forcing the free end of said arm upward and outward.

17. The combination with the car, of a vertical support secured to the car, a mail-bag arm slidable on the support, and a counterbalance connected with said arm.

18. The combination with the car, of a hollow upright secured to the car, a weight in said upright, a mail-bag arm slidable on said upright, and a cord connecting said weight with the mail-bag arm.

19. The combination with the car, of a hollow upright secured to the car and having an opening near its upper end and a pulley in said opening, a weight in said upright, a mail-bag arm slidable on said upright, and a cord passing over said pulley and having its ends connected to said weight and the mail-bag arm.

20. The combination with the car, of an upright removably secured to the car, a mail-bag arm rotatable and slidable on said arm, and a cushioning-buffer on the car against which said arm is held when lowered.

21. The combination with the car, of a mail-bag arm held to the car above the floor thereof and having its outer end extending below the level of said floor, and means for elevating said arm to bring the outer end above the floor and permit of drawing the same into the car.

22. The combination with the car, of a hollow upright, a gudgeon secured to the floor of the car over which said upright is placed, a socket secured to the car into which the upper end of the upright is removably held, and a mail-bag arm on said upright.

23. The combination with the car, of an upright secured to the car, a mail-bag arm slidable on said upright, and a cushioning-buffer comprising a horizontal portion and a

vertical portion against which the bottom and one side of the mail-bag arm bear to relieve the same of jar.

24. A mail-bag receiver, comprising a receptacle, and a pivoted cover having depending sides.

25. A mail-bag receiver, comprising a receptacle and a hinged cover having collapsible sides.

26. A mail-bag receiver, comprising a receptacle, and a cover pivoted to the receptacle and having depending sides, each side comprising a rigid section and a movable section.

27. A mail-bag receiver, comprising a receptacle, a top pivoted between its ends to said receptacle and having collapsible depending sides formed in sections, and links connecting said sections.

28. A mail-bag receiver, comprising a receptacle, a top pivoted between its ends to said receptacle and having collapsible depending sides, each side comprising a rigid section and a movable section connected with said rigid section, and links connecting said sections and adapted to cause the movable sections to swing between the rigid sections when closing the receiver.

29. In a mail-bag receiver, the combination of a receptacle, a gate therefor, and a mail-bag support embodying means to hold said gate open when supporting a bag.

30. In a mail-bag receiver, the combination of a receptacle, a gate therefor, and a mail-bag support secured to said gate and embodying means to hold the latter open when supporting a bag.

31. In an apparatus for catching and delivering mail-bags, the combination with a catching device and a delivering device, of a receiver, means for supporting a mail-bag on said receiver and for automatically closing the receiver when the bag on the receiver is taken up by the catching device.

32. In a mail-bag receiver, the combination of a receptacle, a cover pivotally attached between its ends to said receptacle, a mail-bag support on said cover, means on said cover for retaining a mail-bag on said support, and means for causing said cover to close when the mail-bag is removed from said support.

33. In a mail-bag receiver, the combination of a receptacle, a cover pivotally attached to said receptacle, a mail-bag support pivotally held, connections between said support and the cover for opening the latter on swinging the support into an upright position, and for causing said support to swing into a horizontal position when the cover closes by gravity, and a mail-bag carried on said support and having its ends attached to the cover, said mail-bag serving to hold the support and said cover elevated.

34. In a mail-bag receiver, the combination of a receptacle, a cover pivoted between its ends to said receptacle and having depending sides comprising fixed sections and movable sections, links connecting the outer ends of the movable sections with the fixed sections of said sides, a rod connecting the inner ends of the movable sections, a mail-bag support pivotally affixed to the cover and having a depending portion attached to said rod and a yoke portion lying outside of the cover, a mail-bag on said support having its ends attached to the cover, said cover and said support being adapted to swing into a horizontal position on removing the mail-bag from said support.

35. In a mail-bag receiver, the combination of the receptacle, a cover pivotally secured to said receptacle and normally closed, and a mail-bag supported on the cover and serving to hold the same open.

36. In an apparatus for delivering mail, the combination with a mail-delivering device and a mail-catching device, of a receiver carrying a bag to be taken up by said catching device and comprising a receptacle and a movable cover for said receptacle, said cover when elevated providing a receiving-opening larger than the height of the receptacle.

37. The combination of a car having an opening in its side, and a mail-bag arm extending outward through said opening and having its outer end below the lower end of said opening.

38. The combination of a car having an opening in its side, and a mail-bag arm extending outward through said opening and having its outer end terminating in a plane below the floor of the car.

39. The combination with the car, of a horizontally-swinging arm having its outer end terminating in a plane below the floor of the car.

40. The combination of a car having an opening in its side, and a mail-bag arm having a mail-catching and a mail-delivering device, said arm being arranged for movement outward to bring said catching and delivering devices below the lower end of said opening.

41. The combination with a relatively stationary element provided with catching and delivering devices, of a traveling element provided with coacting catching and delivering devices, a vertically-movable frame on the traveling element carrying the catching and delivering devices thereof, and means for raising and lowering said frame.

In testimony whereof I have affixed my signature in the presence of two subscribing witnesses.

ERIC A. NASLUND.
